UNITED STATES PATENT OFFICE.

HENRY W. STOCK, OF ERIE, PENNSYLVANIA, ASSIGNOR TO GENERAL ELECTRIC COMPANY, A CORPORATION OF NEW YORK.

RADIATOR FOR MOTOR-CARS.

1,154,072.

Specification of Letters Patent. Patented Sept. 21, 1915.

Application filed May 29, 1912. Serial No. 700,407.

To all whom it may concern:

Be it known that I, HENRY W. STOCK, a citizen of the United States, residing at Erie, county of Erie, State of Pennsylvania, 5 have invented certain new and useful Improvements in Radiators for Motor-Cars, of which the following is a specification.

The present invention relates to radiators for motor cars of the type which are constructed and arranged to run on the rails of 10 existing steam or surface roads wherein an internal combustion engine is employed as the motive power agent. This engine may be directly or indirectly connected to the 15 axles of the trucks. Such an arrangement requires a radiator of relatively large area to dissipate the heat transferred to the circulating water through the walls of the cylinders, valve casings, etc. In order to obtain 20 the best-cooling effects the radiator, its headers, jackets, piping, etc., should be substantially filled with water or other cooling liquid.

In carrying out my invention, a radiator 25 is provided comprising a plurality of tubes which are connected to headers and the whole structure is mounted on the roof of the vehicle where it is subjected to the cooling effects of air currents, particularly when 30 the vehicle is in motion. I have found in the practical operation of such apparatus that when the vehicle is stopped suddenly and to a lesser extent when it is so started, that the water in the headers surges back 35 and forth, often spilling out of the overflow resulting in waste which is detrimental to good operation, is wasteful and also tends to disfigure the appearance of the vehicle by reason of the water running down the sides 40 of the vehicle over the window, etc. I have also discovered that at times when the engine is running at too high a temperature, usually due to unskilled operation, steam will be formed in the engine jackets which 45 blows water out of them and causes a discharge at the overflow. I have also found that when the vehicle is traveling on steep grades that the water will sometimes collect in one end of the radiator causing a fictitious 50 level at that point with a resulting overflow at the outlet. To avoid these objections I provide what for convenience may be termed an overflow tank or receptacle which, as an additional function, may serve to

equalize the level of the water in the right 55 and left-hand sections of the radiator. This tank may be of any suitable size but it should be at least equal to the cubical contents of the cylinder and valve jackets of the engine so that if they discharge the water 60 contained therein due to the momentary formation of steam, it can all be received in said tank and later flow back to the radiator. The tank should be so arranged that the entrance of water into it is baffled or retarded 65 to a certain degree so as to limit the effects of surging to a greater or less degree.

In the accompanying drawing which illustrates one of the embodiments of my invention, Figure 1 is a portion of a self-propelled vehicle showing the engine radiator in elevation and the body of the vehicle in outline, and Fig. 2 is a longitudinal section taken on line 1—2 of Fig. 1.

5 indicates the floor of the vehicle, 6 the 75 side-walls thereof, and 7 the roof. I have omitted the trucks from the vehicle because they are unnecessary to an understanding of the invention.

Located within the vehicle is an internal 80 combustion engine 8 of any suitable construction. As shown, the engine comprises eight cylinders arranged in sets of four each, the cylinders being inclined to each other. The pistons in the cylinders are connected 85 by suitable cranks to the main shaft 9; the latter may be directly connected to the car axles through gearing or indirectly through an electric generator and motors. I prefer the latter arrangement. The engine cylinders and valve casings are provided with cooling jackets 11 and cooling water is conveyed thereto by the conduits 12 and conveyed therefrom by conduits 13 to the radiator. In these conduits are flexible connections 90 14. The radiator which is mounted on the roof of the vehicle and corresponds approximately to the curvature thereof, is made in two principal parts or sections. Each of these parts comprises headers 15 95 and 16 which are connected to an inner set of tubes 17 and an outer set 18. Each of these tubes is provided with radiating fins to increase the effective cooling surface.

Mounted on top of the upper headers 16 is 100 an overflow tank or receptacle 19 which is connected to each of the headers 16 by relatively restricted openings or orifices 20 and

21. These are located near the ends of the overflow tank so that as the water tends to surge back and forth in the header under conditions of starting and stopping, it can enter the tank. These openings are relatively restricted so that a certain amount of opposition will be offered to the movements of the water. The tank is similarly connected to the right-hand header so that it will receive water from both parts or sections of the radiator and return it to them when the conditions become normal. The cubical contents of the overflow tank should be at least equal to those of all engine jackets, if the best effects are to be obtained. That is to say, if steam is generated in the jackets and blows the water out of them, the overflow tank should have a capacity great enough to receive this water.
20. Each of the headers 16 is provided with a filling and overflow device 22 having a cap 23 to prevent the entrance of foreign matter. Between the upper and lower sets of tubes 17 and 18 is a baffle 24 comprising a partition attached to the side and end walls of the header and containing a plurality of orifices 25. This baffle serves to distribute the cooling water to the various tubes in each set and also assists in retarding the surging action of the water in the operation of the vehicle.

I have shown the overflow tank mounted on top of the radiator headers because this is a very effective location, but it is not necessarily so positioned. The tank may be of any suitable shape and can be made larger than above specified if desired. It is important, however, from a constructive and operative standpoint to make it as small as possible consistent with satisfactory operation. This is particularly true where head room in the car-barns, of the bridges, etc., is limited.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

35. 1. In a vehicle, the combination of an internal combustion engine located within the vehicle and having a fluid cooling system, a radiator made in two principal parts or sections located at opposite sides of the vehicle, receiving and delivery connections between each of said sections and said cooling system, so that the fluid from the latter may pass through them and give up heat, and, in addition, an overflow receptacle common to both sections of the radiator and located

above them which is adapted to receive fluid temporarily forced upward from the radiator by movement of the vehicle or by steam generation in the fluid cooling system of the engine.

2. In a vehicle, the combination of an internal combustion engine having its cylinders arranged in sets and also having a cooling system for each set located within the vehicle, a radiator for each system outside the vehicle, receiving and delivery connections between each radiator and the corresponding cooling system, and, in addition, an overflow tank on the roof of the vehicle that is connected to both of them and is arranged to receive fluid expelled therefrom as a result of the generation of steam or of surging otherwise brought about and subsequently to return it.

3. In a vehicle, the combination of an internal combustion engine carried thereby and having a fluid cooling system, a radiator comprising headers and connecting conduits located outside of said vehicle, receiving and delivery connections between said radiator and said cooling system, and, in addition, an overflow tank located above the radiator and connected to one of its headers through a relatively restricted opening.

4. In a vehicle, the combination of an internal combustion engine carried thereby and having a fluid cooling system, a radiator comprising headers and connecting conduits arranged in sets located outside of the vehicle, there being a baffle in one of the headers between the sets to distribute the fluid to the conduits and reduce the effects of surging, receiving and delivery connections between said radiator and said cooling system, and, in addition, an overflow tank located above the radiator and connected thereto at separate points.

5. In a vehicle, the combination of an internal combustion engine carried thereby and having a fluid cooling system, a radiator located on the roof of the vehicle and comprising two sections each with a plurality of headers connected by radiating conduits, receiving and delivery connections between said radiator and said cooling system, and, in addition, an overflow tank located above two of said headers and in open communication with both.

6. In a self-propelled vehicle, the combination of an internal combustion engine located within the vehicle and provided with cooling jackets, a radiator located on the roof of the vehicle, conduits connecting the engine jackets and the radiator, and in addition an overflow tank also located on the roof of the vehicle which is in communication with the radiator.

7. In a vehicle, the combination of an internal combustion engine mounted thereon and having cooling jackets, a radiator

mounted outside said vehicle, receiving and delivery connections between the cooling jackets and said radiator, and, in addition, a receptacle located above said radiator and connected directly therewith at a point above the normal level of the cooling fluid, said receptacle being normally empty and of such size that its cubical contents are at

least approximately equal to those of the engine jackets.

In witness whereof, I have hereunto set my hand this 23rd day of May, 1912.

HENRY W. STOCK.
